UNITED STATES PATENT OFFICE.

WILLIAM K. LIGGETT, OF COLUMBUS, OHIO, ASSIGNOR TO THE JEFFREY MANUFACTURING COMPANY, A CORPORATION OF OHIO.

PULVERIZING APPARATUS.

1,169,501.

Specification of Letters Patent. Patented Jan. 25, 1916.

Original application filed February 18, 1907, Serial No. 357,914. Divided and this application filed April 9, 1908, Serial No. 426,150. Renewed June 17, 1915. Serial No. 34,738.

To all whom it may concern:

Be it known that I, WILLIAM K. LIGGETT, a citizen of the United States, residing at Columbus, in the county of Franklin and State of Ohio, have invented certain new and useful Improvements in Pulverizing Apparatus, of which the following is a specification, reference being had therein to the accompanying drawing.

10 This invention relates to pulverizers, and has for its objects, first, to provide an improved hammer mechanism, and, secondly, to so construct the rotating parts that they act as a fan blower as well as to crush and 15 pulverize the material.

This application is a division of my application, Sr. No. 357,914, filed Feb. 18, 1907.

In the drawings: Figure 1 is a longitudinal section of an apparatus embodying my 20 invention. Fig. 2 is a top plan view of the same. Fig. 3 is a vertical transverse sectional view looking toward the feed hopper.

In the drawings, the shaft 1 is shown mounted in the bearings 2—2 and provided 25 with a pulley 3 which is adapted to be belted to any suitable source of power. The bearings 2 are carried by the base 4 which likewise supports the casing 5. This casing is 30 constructed in the usual manner and is provided with the grinding plates 27 made of material suitable for the purpose of co-acting with the hammers to grind the rock, coal, ore or other material.

Material is fed into the casing from the 35 feed plate 8 which is arranged below the opening 6 in the feed hopper 7. The feed plate is reciprocated on a track way by any suitable means, that shown comprising the pitman 9, crank 10, shaft 11 on which the 40 crank is mounted, the latter receiving its motion through suitable gearing 12—13, and the power shaft 14, which is operatively connected to the shaft 1.

I have shown this pulverizer as connected 45 to air inlet and outlet pipes which are designed to lead to and from collecting and separating apparatus, or the outlet pipe may be merely a means of delivering material at the desired point and the inlet pipe may 50 merely serve to guide air from the surrounding atmosphere to the interior of the machine. But some of the improvements described and shown in the drawings are equally applicable to machines in which

the material is removed from the pulverizing chamber through grate bars or in any other manner. 55

By means of the feeding mechanism above described, a comparatively air-tight inlet opening is provided for the material. Air 60 is drawn in through the central lateral openings in the casing 15—15, the latter being connected to any desired source of air supply by means of the pipes 16—16 or to the collecting and separating devices to receive 65 insufficiently pulverized material and return it to the pulverizer. The discharge opening 17 is preferably located at the top of the pulverizing chamber, and the pipe 18 serves to carry the pulverulent material wherever 70 may be desired. The opening 17 is approximately of the same width as the pulverizing chamber, but the discharge duct 18 widens rapidly above this opening in longitudinal 75 planes, as shown in Fig. 3, to form the enlarged chamber 19. In this chamber are mounted baffle plates 20 which serve to prevent the discharge of undesirably large pieces of material and to return them to the pulverizing chamber to be more finely divided. 80 Upon the shaft 1 are mounted in close proximity to each other the annular disks 21—21 having the annular part 22 and the spokes 23. A chamber or passageway 26 is formed between the annular parts 85 22 and the spokes 23 of the disks. This chamber is concentric with the axis and serves as a passageway for air as well as for material suspended in the air. Between these disks are mounted hammers 24—24 90 which are pivotally carried by the rods 25, the latter being supported in the annular portions of the disks. These hammers are flat, metal bars, which between their ends are given a twist through an angle of between 45 and 90 degrees. The bars are of 95 such a width and are mounted at such a distance apart that when given this twist the blade portions overlap each other. By constructing and mounting the hammers in this 100 way, the blade portions act like the vanes in centrifugal fans, and draw air in through the lateral openings 15, 15, into the drum-like chamber 26 and radially outward against the peripheral walls of the casing. 105 By giving the ends of the blades a twist through an angle of approximately 45 degrees, or such an angle that the blades are

inclined to the axis of the pulverizer shaft as well as to their circles of rotation, a peculiarly effective grinding action is secured between the blades and the grinding plates 5 27. The particles of material are thrown and rubbed in directions both transverse of the machine and circumferentially. The overlapping of the blades also prevents any part of the material from passing between 10 the hammers unground and facilitates the reduction of the material.

What I claim is:

1. In a pulverizing apparatus, the combination of a casing having a grinding surface, a rotary horizontal shaft mounted in the casing, a hammer-carrying mechanism mounted on the shaft and formed with a chamber 26 concentric with the axis and open at both ends, the chamber having radial 15 openings at intervals throughout its length, a series of hammers mounted on the hammer-carrying mechanism, and adapted to co-operate with the said grinding surface, means in the planes of rotation of the hammers for supplying to the casing material 20 25

to be pulverized, and means for feeding material to the said chamber 26 at both ends thereof, the material fed to the chamber passing out through the radial openings to be acted upon by the hammers. 30

2. In a pulverizing apparatus, the combination of a casing, a rotating pulverizing element mounted therein, arranged to act also as a fan, a duct through which the material is carried along with the air currents 35 produced by said rotating element, the duct expanding immediately above the casing, and a deflector 20 situated in the duct directly above and opposite the opening into the casing and concaved downward to arrest 40 the larger particles of material carried out of the casing and to return them thereto through the said duct, substantially as set forth.

In testimony whereof I affix my signature, 45 in presence of two witnesses.

WILLIAM K. LIGGETT.
